ELEVATOR CONTROL SYSTEM

Application filed March 29, 1927. Serial No. 179,243.

My invention relates to a push-button control system for elevators, with circuits controlled by a movable or scale-beam platform.

In push-button control circuits for elevators, it is common practice to include a car gate switch in the operating circuit so that movement of the car cannot be effected by hall or car push-buttons until the car gate is in closed position. But it frequently happens that the car gate is left open by the last passenger to leave the car, thus tying up the system as this prevents dispatch of the car from the hall push-buttons.

One of the objects of this invention is to provide an electro-magnet energized by the hall button circuits for closing the car gate switch or a by-pass circuit around it, and to mechanically connect such magnet with a movable car platform in such a way that any load on the platform will render the magnet inoperative. Such an arrangement in effect provides means to control the switch in accordance with tell-tale positions of the platform, so that the magnet with the platform unoccupied and the car gate open, renders the system operable for hall button dispatch, but with the platform occupied closure of the car gate is necessary to render the system operable for car button dispatch.

Another object of the invention is to provide an electro-magnet movable by the movable car platform to control multiple switches, one of which controls a by-pass circuit around the car gate switch and the other a car light circuit to be opened when the car is unoccupied and not under dispatch, but to be closed when the car is unoccupied and under dispatch by a hall button, so that the empty car will arrive lighted at its destination, the car light switch having a delayed opening at such time and being arranged to remain closed so long as the car is occupied.

Another object of the invention is to provide non-interference contactors for a push-button system of circuits to be controlled by mechanism of a novel construction having a new mode of operation.

A still further object of the invention is to provide push-button controlled circuits exclusive of the car gate switch and reversing

switch windings whereby operation of a car or hall button conditions the system to establish direction for car travel and predetermines the stop without effecting car movement. By including the car gate switch in an independent circuit with the reversing switch windings, car movement may be effected by hall button operation, by means of an electro-responsive device by which the car gate switch may be closed even if the car is unoccupied.

Other objects of the invention will appear hereinafter, the novel combinations of elements and arrangement of parts being pointed out in the appended claims.

Referring to the accompanying drawings, Fig. 1 illustrates in a more or less diagrammatic manner, a push-button control system embodying the present invention; and

Figs. 2 to 4 inclusive illustrate alternative constructions and also modified systems of circuits.

In the drawings, C designates the elevator car, comprising in its construction a platform D supported by scale-beam apparatus E to have vertical movement to two different positions indicative of car platform condition as to whether it is occupied or unoccupied. A car gate G may be of any well known type adapted to be closed manually. Secured to the gate is a roller 4 to coact with the car gate switch or circuit controller H to close the same with the car gate in closed position by engaging a movable member such as the pivoted arm 1, and movement of the gate to open position disengages the roller from said arm to permit the latter to open the car gate switch.

Other elements which go to make up the push-button control system comprise hall and car push-buttons designated *h. b.* and *c. b.*, floor relays *f. r.*, floor stop controlling mechanism *f. s.*, up and down direction relays 8 and 9 respectively, hoistway door contacts 12, non-interference switch 10, holding relay 11, and up and down reversing switches R and R' respectively.

In accordance with the present invention in the form shown in Fig. 1, the car gate switch arm 1 constitutes the armature for an

electro-magnet K. The electro-magnet is connected by a rod and lever connection 6 to the scale-beam lever 7, by which it is rotated bodily about a support 5. When the car platform is in unoccupied position, the electro-magnet K is in operative position as shown with respect to its armature or switch arm 1, so that when energized its magnetic lines are effective to actuate the switch arm to close the car gate switch. With the car platform in occupied position the electro-magnet is rotated into inoperative position so that its magnetic lines are ineffective to close the car gate switch.

In accordance with the present arrangement of circuits, the car gate switch and the reversing switch windings are in a circuit exclusive of the push-button circuits, so that with the car at rest and all circuits dead, all the hoistway doors closed and the car gate in open position, any floor relay other than the one corresponding to the landing at which the car is standing, can be set by button operation together with an up or a down direction relay, depending on car position and the button pressed. Thus the push-button system is conditioned to predetermine the car stop and establish direction for car movement, with the car gate open, without effecting car movement. This is so because the circuits for the reversing switch windings are exclusive of the push-button circuits and are controlled by the car gate switch also exclusive of the push-button circuits, but dominated by the hoistway door contacts. Hence, with all hoistway doors closed, car movement is rendered effective by closing the car gate switch to complete at that point an energizing circuit for an up or a down reversing switch winding in accordance with the direction relay closed by button operation. The electro-magnet K is energized by either hall or car button operation and will be rendered effective by movement of the car platform when unoccupied to close the car gate switch or will be ineffective to close this switch if the car is occupied. Therefore, the electro-magnet K is positioned by the platform position to close the car gate switch only when the car platform is in unoccupied tell-tale position, to render car movement effective by hall-button operation even though the car gate be in open position.

Let us assume that the unoccupied car is at the third floor landing with the car gate and car gate switch open and all the hoistway doors closed, and that the first floor hall button 20 is momentarily pressed. By pressing this button a circuit is closed as follows: from a plus main 21, through the hoistway door contacts 12 to wire 23, noninterference relay 10, wire 24, hall button 20 to wire 25, first floor relay winding 19 to wire 26, floor controller f. s. to wire 27, winding 28 of the down direction relay 9, wire 29, back

contacts 30 of up direction switch 8, and thence by wire 31 to the minus line. The down relay 9 now operates to close its contacts 13 in a circuit for the down reversing switch winding 32 to establish direction for car travel. This reversing switch winding circuit is exclusive of the floor relays and is dominated by the hoistway door contacts and the car gate switch, so that even though a floor relay and direction relay may be set by hall button operation with the car gate switch and car gate open, the hoisting operation is not rendered effective until the car gate switch and all the hoistway doors are closed to complete an energizing circuit for the down reversing switch winding 32. With the car platform unoccupied, the electro-magnet K assumes its operative position as illustrated, to which position it is shifted by being bodily rotated through the connection with the car platform by the action of a balancing spring 17 which moves the platform upwardly as the last passenger steps therefrom. The electro-magnet K is included in the self-holding circuit 18 for the floor relays and will, therefore, become energized by operation of the first floor relay to close its self-holding contacts 22. The electro-magnet K being energized and in its operative position, will actuate the switch arm 1 to close the car gate switch contacts H and thus complete the circuit for the down reversing switch winding 32 to close the hoisting motor circuits (not shown) and start the car.

The completed circuit for the down reversing switch winding may be traced as follows: the same as heretofore traced up to a junction 33 with the wire 23, wire 34, through car gate switch contacts H, wire 35, top contacts 13 of down direction relay 9, wire 36, down reversing switch winding 32, and thence to the minus line by wire 37.

From the foregoing description it will be seen that movement of the car platform shifts the electro-magnet K to two different tell-tale positions which are indicative of unoccupied and occupied car condition, and that this shifting of magnet position does not of itself affect the contact mechanism which is associated with the magnet.

A passenger first to occupy the car causes its platform to move downwardly a limited distance to be seated against resilient stop members 78. This movement shifts the electro-magnet K bodily, by rotating it to an inoperative position with respect to the car gate switch arm 1. Hence, with the car platform occupied, it becomes necessary in order to render the hoisting operation effective by car button operation, to close the car gate switch by closing the car gate in order to complete the circuit for a reversing switch winding.

From the detailed description already given for hall button operation, it will be

obvious that for car button operation a floor relay and a direction relay can be set with the car gate and car gate switch in open position by a passenger in the car pressing 5 a car button, but without effecting car movement, and that the hoisting operation is rendered effective by closing the car gate to close the car gate switch.

The non-interference relay 10 operates in a 10 well known manner to prevent interference to car movement while under car button or hall button dispatch, this relay operating in conjunction with the self-holding relay 11 for car button operation in a manner to prevent 15 restoration of the hall button feed circuit when the car stops, unless and until a hatchway door has been opened and again closed.

In the Fig. 2 illustration, the system of circuits is substantially the same as in Fig. 1, 20 excepting that herein a switch 38 controls a by-pass circuit 39 around the car gate switch which is closed when the car platform is unoccupied to render the hoisting operation effective 25 under such car condition by hall button control even if the car gate is in open position. This by-pass circuit is opened when the car platform is occupied to necessitate closure of the car gate to render the hoisting operation effective by car button control. The electro-magnet K' in this instance is supported by a vertically movable guide rod 40 which through tell-tale movement of the car platform shifts the electro-magnet K' bodily 29 in a straight line movement with respect to 30 its plunger 41 which is connected to the switch arm 42. With such an arrangement, when the platform is unoccupied the magnet is caused to shift by movement of the platform to decrease 35 the air gap between the plunger and the core 43 of the electro-magnet, so that when the magnet is energized its magnetic lines are effective to actuate the plunger to close the by-pass switch 38. By closing the 40 by-pass switch 38, the hoisting operation is rendered effective by hall button operation, with the car gate and car gate switch open and the car unoccupied, in the same manner as effected by closing the car gate switch by 45 the shiftable magnet K in the Fig. 1 illustration.

Movement of the car platform as effected by the first passenger to step thereon shifts the electro-magnet K' to increase the air gap 50 to such an extent so that when the electro-magnet is energized, as by car button operation, its magnetic lines are ineffective to actuate the plunger so that the by-pass switch 38 remains open. Hence, in order to render 55 the hoisting operation effective by car button control, the car gate must be closed to close the car gate switch.

In the Fig. 3 illustration, the circuits are 60 substantially the same as in Fig. 2, the essential difference residing in the provision

of an electro-magnetically operable by-pass switch 38' of a modified construction. In this modified construction, one of the contacts of the by-pass switch 38' is moved from an inoperative position indicated by dotted lines to an operative position illustrated in full lines within range of its coacting contact. This movement effected by the car platform does not close the switch, but places one contact in position to be engaged by its coacting contact when the latter is actuated by energization of the electro-magnet K², and in such manner the by-pass switch is closed.

It will thus be seen that the car platform shifts but does not close a contact by its movement when unoccupied as by the last passenger stepping therefrom, but closing of the contacts is then rendered effective by energization of the electro-magnet K². Hence, the closed by-pass switch renders the hoisting 85 operation effective as controlled by hall button operation with the car gate and the car gate switch open if the car is unoccupied.

Movement of the car platform as effected by the first passenger to step thereon, shifts 90 the contact to the position indicated by dotted lines out of range of its coacting contact when moved to actuated position as effected by the electro-magnet K². The by-pass switch is maintained in such open-circuited 95 position so long as the car platform is occupied, thus necessitating closure of the car gate to close the car gate switch to render the hoisting operation effective by car button control.

In the arrangement shown in Fig. 4, the electro-magnet K³ is permanently energized and is shiftable bodily by movement of the car platform so that for unoccupied condition of the latter the electro-magnet assumes 105 an operative position with respect to a switch 51, magnetically to close same against the action of a spring 61 to close a by-pass circuit 62 around the car gate switch. The system is thereby rendered operable for dispatch operation by the hall buttons with the car platform unoccupied even with the car gate and car gate switch in open position. With the system of push-button control circuits shown, the reversing switch windings are controlled 110 directly by hall and car button operation as in standard practice instead of indirectly as by direction relays as illustrated in the other figures.

The hall button feed circuit may be traced 115 as follows: from a plus wire 21, through hoistway door contacts 12, wire 56 to a junction 57, the by-pass wire 62 and switch 51, to a junction 58, and from thereon to the hall push-buttons by way of a wire 59 which includes two sets of non-interference contacts 44 and 50 in series.

A switch arm 73 controls the non-interference contacts 44 and car light contacts 45, so that with the platform unoccupied and 120

not under dispatch the car light circuit 53 is opened at contacts 45 and also at contacts 46 in a shunt circuit around the contacts 45. However, with the platform unoccupied and under dispatch by a hall button, one of the contacts 46 is shifted by movement of the car platform to a position within range of its co-acting contact so that when the latter is in actuated position as effected by energization of an electro-magnet 47 in the self-holding circuit 48 of the floor relays, it engages the shiftable contact to close the car light circuit. Thus the car light circuit 53 is closed by hall button dispatch of the car, and the empty car will arrive lighted. The electro-magnet 47 is de-energized when the car stops, as by the automatic opening of a floor relay, but the opening of the switch 46 is delayed by a dash-pot 49 in order to maintain the light circuit closed subsequently to car stop, a sufficient length of time to enable a passenger without delay to enter the car. If the hall passenger should not enter the car, it is evident that the light circuit will be opened at the switch 46 at the expiration of a short period of time. But if the hall passenger does enter the car, his act of stepping onto the car platform moves the platform, and by so doing shifts the electro-magnet K³ downwardly to an inoperative position with respect to the by-pass switch 51 and into operative position with respect to the switch arm 73. In such shifted position of the electro-magnet, it operates magnetically to instantaneously open the hall button feed circuit 59 at the contacts 44 to thus render the hall buttons inoperative as soon as and while the car platform is occupied, and at the same time close the contacts 45 to close the car light circuit at that point. In such manner the car light circuit is closed by a second circuit controlled magnetically by the electro-magnet K³ and indirectly by movement of the car platform.

Since by occupying the car platform it is moved to shift the electro-magnet K³ to an inoperative position so that its magnetic lines are rendered ineffective with respect to the switch 51, the latter will thereby be rendered operable to be opened by the spring 61. Opening switch 51 opens the by-pass circuit around the car gate switch so that it becomes necessary to close the car gate to close the car gate switch in order to close the car button feed wire 52 in order to render the car buttons operable to dispatch the car.

It may be desirable to allow a short time period to elapse after the last passenger steps off the car platform before restoration of the hall button feed circuit at the contacts 44 is effected. To this end a dash-pot 80 may be provided for the switch arm 73. Or a dash-pot (not shown) to retard the return movement of the car platform will accomplish the same result. The magnet being movable with

the platform will magnetically hold the contacts 45 closed during an appreciable movement of the electro-magnet away from the switch arm 73, and when such movement is sufficient to render the magnetic lines ineffective to attract arm 73, the spring 77 will act to close the non-interference contacts 44 and open the car light circuit contacts 45. The magnet K³ will then be in position to close the contacts 51.

For hall button dispatch of the car, energization of the electro-magnet 47 actuates one of the contacts 46 to engage its cooperating shiftable contact to close the car light circuit. Such engagement of the contacts 46 open-circuits back contacts 50, both of which are shiftable bodily together with the magnet K³ and with one of the contacts 46. Said contacts 50 are in series with the non-interference contacts 44 in the feed circuit of the hall push-buttons, and since the contacts 44 are closed with the car platform unoccupied, they will not function to prevent interference to movement of the car while under hall button dispatch. However, for unoccupied car condition, it will be seen that back contacts 50 are open-circuited by energization of the electro-magnet 47 when a floor relay closes its self-holding circuit and thus interference to movement of car while under dispatch by a hall button is prevented. The dash-pot 49, by delaying the opening of the light circuit contacts 46, likewise will delay the closing of the non-interference contacts 50, so that a hall passenger is given ample time to open the hoistway door and occupy the car before restoration of the hall button feed circuit at contacts 50.

It will be seen that the electro-magnet provided herein, as in Fig. 1 for example, controlled by tell-tale movement of the car platform, provides in effect a lost motion connection between the movable car platform and the car gate switch whereby the electro-magnet or actuating means for the gate switch is moved to operative and inoperative positions without moving its associated switch mechanism. Furthermore, it will be seen that the energization of the electro-magnet is controlled manually in both of its tell-tale positions but that it is effective in only one of said positions magnetically to influence the switch to control its closing and opening, and that when it is in its inoperative or ineffective positions, as it is when anyone is in the car, the gate switch can be closed only by closure of the car gate.

Having thus described the invention, what I claim is new and desire to secure by Letters Patent of the United States is:

1. A system of control for elevators comprising in combination, a car having a gate, a car gate switch, closable when the car is occupied only by the car gate, and magnetic

70

means for closing said switch with the car unoccupied.

2. A system of control for elevators comprising in combination, a car having a gate, push-button control circuits, and a car gate switch exclusive of said circuits and controlled to be closed magnetically to effect car dispatch.

3. A system of control for elevators comprising in combination, a car having a gate, a car gate switch controlled thereby, selectively operable hall push-button controlled circuits, and electro-responsive means controlled by said push-buttons to close said switch and thereby effect car dispatch.

4. A system of control for elevators comprising in combination, a car gate switch, and manually controlled electro-responsive means to close the car gate switch.

5. A system of control for elevators comprising in combination, a car having a gate, a car gate switch controlled thereby, reversing switches having operating windings, said car gate switch being in the circuit of said windings, and electro-responsive means arranged to close said car gate switch.

6. A system of control for elevators comprising in combination, a car having a gate, a car gate switch controlled thereby, selectively operable hall and car push-button controlled circuits exclusive of said gate switch, reversing switches having operative windings and having a circuit controlled by said car gate switch to close said reversing switches to effect car dispatch, and electro-responsive means controlled by said push-button circuits to close said car gate switch.

7. A system of control for elevators comprising in combination, a car having a tell-tale movable platform, and an electro-magnetically operable switch, part of which is movable by said tell-tale platform movement to render it effective to close the switch with the platform unoccupied, and ineffective to close the switch with the car occupied.

8. In combination, an elevator car having a platform movable independently of the car frame, a power device movable by said platform movement, and a member adapted to be actuated by said power device.

9. In combination, an elevator car having a platform movable independently of the car frame, and a magnet having its air gap changed by movement of said platform.

10. In combination, an elevator car having a platform movable independently of the car frame, an electro-magnet having its air gap changed by movement of said platform, and means to be influenced and non-influenced by said electro-magnet, depending on such change of air gap.

11. In combination, an elevator car having a platform movable independently of the car frame, a push-button system of control comprising an electro-magnetically operable non-

interference switch mechanism, part of which is movable by said platform to render the magnetic effect effective to open-circuit said mechanism when the platform is occupied.

12. In an elevator system, a weight responsive element associated with a car, arranged to assume different positions when the car is occupied or unoccupied, a movable member, means to control car operation, and a power device for the movable member controlled by said car control means and conditioned by said element to render the said device effective or ineffective to move said member.

13. In an elevator system, a weight responsive element associated with a car, arranged to assume different positions when the car is occupied or unoccupied, a movable member, means for actuating said movable member operatively controlled by said element, and manually operable means for rendering the operation of said actuating means effective to move said member.

14. In an elevator system, a weight responsive element associated with a car, arranged to assume different positions when the car is occupied or unoccupied, a movable member, and a power device movable by said weight responsive element to render its influence effective to actuate said member when said element and said device are in only one of their positions.

15. In an elevator system, a weight responsive element associated with a car, arranged to assume different positions when the car is occupied or unoccupied, a movable member, a power device for actuating said member, manual means for controlling the energization thereof, said device being movable by said element to positions to render its influence operative or inoperative.

16. In an elevator system, a weight responsive element associated with a car, arranged to assume different positions when the car is occupied or unoccupied, a movable member, a power device for actuating said member, manual and automatic means for controlling the power supply to the device, said device being movable by said element to positions to render its influence on the movable member effective and ineffective.

17. In an elevator system, a weight responsive element associated with a car, arranged to assume different positions when the car is occupied or unoccupied, and independently operable circuit closing means connected with and positioned by said element when the latter assumes one of such positions for effective operation independently of said element to close a circuit.

18. In an elevator system, a weight responsive element associated with a car, arranged to assume different positions when the car is occupied or unoccupied, a circuit controller, and means conditioned by such ele-

ment for effective operation independently of said element upon said circuit controller.

19. In an elevator system, a weight responsive element associated with a car, arranged to assume different positions when the car is occupied or unoccupied, a circuit controller, and electro-responsive means conditioned by said element, to thereby render it operative to actuate said circuit controller when said element assumes one of its positions.

20. In an elevator system, a weight responsive element associated with a car, arranged to assume different positions when the car is occupied or unoccupied, a circuit controller, and means positioned upon said element assuming one of its positions to actuate said circuit controller, and moved out of operative position upon the element assuming its other position.

21. In an elevator system, a weight responsive element associated with a car, arranged to assume different positions when the car is occupied or unoccupied, a circuit controller, electro-responsive means for actuating the circuit controller, manually operable means for controlling the energization thereof, and means controlled by said element to position said actuating means relative to the circuit controller and thereby render its influence effective or ineffective.

22. In an elevator system, a weight responsive element associated with a car, arranged to assume different positions when the car is occupied or unoccupied, a circuit controller, and a power device for actuating the circuit controller arranged to be energized with said element in either of its positions, and being movable by said element to operative and inoperative positions.

23. In an elevator system, a weight responsive element associated with a car, arranged to assume different positions when the car is occupied or unoccupied, a circuit controller, a power device for actuating the circuit controller, said device exerting its influence in both positions of said element and being movable by said element to positions to render its influence effective when the element is in only one of its positions.

24. In an elevator system, a weight responsive element associated with a car, arranged to assume different positions when the car is occupied or unoccupied, a circuit controller, a power device for actuating said circuit controller movable by said element to render its influence on the circuit controller effective and ineffective, manual means to connect said device with a source of power supply, and means automatically to disconnect said device from the source of supply.

25. In an elevator system, a weight responsive element associated with a car, arranged to have a tell-tale movement, and electro-magnetically operable means on the car con-

trolled by said tell-tale movement of said element to render its magnetic effect operative and inoperative.

26. In an elevator system, a weight responsive element associated with a car, arranged to have a tell-tale movement, and an electro-magnetically operable device, part of which is movable to different positions by the tell-tale movement of said element, one of which renders the magnetic effect operative and the other inoperative. 75

27. In an elevator system, a weight responsive element associated with a car, arranged to have a tell-tale movement, and an electro-magnetically operable device, part of which is movable to different positions by the tell-tale movement of said element, one of which renders the magnetic effect effective to actuate another part of said device. 80

28. In an elevator system, a weight responsive element associated with a car, arranged to have a tell-tale movement, and a magnet movable by the tell-tale movement of said element to operative and inoperative positions. 85

29. In an elevator system, a weight responsive element associated with a car, arranged to have a tell-tale movement, and a magnet having its air gap changed in accordance with the tell-tale movement of said element. 90

30. In an elevator system, a weight responsive element associated with a car, arranged to have a tell-tale movement, an electro-magnet and armature therefor, one of the two being movable independently of the other by the tell-tale movement of said element to change the air gap to render the electro-magnet effective and ineffective. 100

31. In an elevator system, a weight responsive element associated with a car, arranged to have a tell-tale movement, and an electro-magnetically operable switch, part of which is movable to different positions by the tell-tale movement of said element, one of which renders the magnetic effect effective to close said switch, and the other of which renders it ineffective to close said switch. 110

32. In an elevator system, a weight responsive element associated with a car, arranged to have a tell-tale movement, a switch and an electro-magnet, one of the two being movable to different positions by the tell-tale movement of said element to render the energized electro-magnet operative and inoperative to close the switch. 115

33. In an elevator system, a weight responsive element associated with a car, arranged to have a tell-tale movement, a switch and an electro-magnet to actuate said switch, movable to different positions by the tell-tale movement of said element to render its magnetic effect effective and ineffective. 125

34. In an elevator system, a weight responsive element associated with a car, ar- 130

arranged to have a tell-tale movement, a switch, and an electro-magnet to actuate said switch, movable to different positions by the tell-tale movement of said element to render its magnetic effect effective and ineffective, and

5 means independent of the movement of said element for controlling the energization of said magnet.

35. In an elevator system, a weight responsive element associated with a car, arranged to have a tell-tale movement, a switch, an electro-magnet to actuate said switch, movable to different positions by the tell-tale movement of said element to render its magnetic effect effective and ineffective, manual

10 means to close an energizing circuit for said electro-magnet, and means controlled automatically by the car to open said circuit.

36. In an elevator system, a weight responsive element associated with a car, arranged to have a tell-tale movement, a selectively operable push-button system of control, a movable member, and a power device to actuate same having its power supply controlled by said push-button system and its influencing effect controlled in accordance with the tell-tale position of said element.

37. In an elevator system, a weight responsive element associated with a car, arranged to have a tell-tale movement, a selectively operable push-button system of control, a circuit controller, and a power device to actuate same having its power supply controlled by said push-button system and its influencing effect controlled in accordance with the tell-tale position of said element.

38. In an elevator system, a weight responsive element associated with a car, arranged to have a tell-tale movement, selectively operable car and hall push-button system of control, a circuit controller and a power device to actuate the same, having its source of power controlled by said push-button system, movable to different positions by the tell-tale position of said element to render its influence effective and ineffective.

39. In an elevator system, a weight responsive element associated with a car, arranged to have a tell-tale movement, a selectively operable push-button system of control, a circuit controller, and a power device to actuate same having its power supply controlled by said push-button system, and being movable by the tell-tale position of said element so that with the car unoccupied it operates to both close and open said circuit controller, and with the car occupied its exerted influence is ineffective to close said circuit controller.

40. In an elevator system, a weight responsive element associated with a car, arranged to have a tell-tale movement, manual control means to establish direction of car dispatch without effecting such dispatch, and an electro-magnetically operable switch con-

trolled in accordance with the tell-tale position of said element to close to effect car dispatch.

41. In an elevator system, a weight responsive element associated with a car, arranged to have a tell-tale movement, selectively operable push-button controlled means to dispatch the car and effect its automatic stop, and an electro-magnetically operable switch to control dispatch of the car, part of said switch being movable by said element to render it effective to close the switch with the car unoccupied.

42. In an elevator system, a weight responsive element associated with a car, arranged to have a tell-tale movement, reversing switches having operating windings, and an electro-magnetically operable switch to control said reversing switch winding circuits, part of which is movable by said element to render it effective to close the switch with the car unoccupied, and ineffective to close the switch with the car occupied.

43. In an elevator system, a weight responsive element associated with a car, arranged to have a tell-tale movement, selectively operable push-button controlled means, reversing switches having operating windings, and an electro-magnetically operable switch operable together with said means to control said reversing switch winding circuits, part of said switch being movable by said element to render it effective to close the switch with the car unoccupied, and ineffective to close the switch with the car occupied.

44. In an elevator system, a weight responsive element associated with a car, arranged to have a tell-tale movement, push-button controlled circuits including non-interference contacts, and electro-responsive means to actuate said contacts, having an air gap changed in accordance with the movement of said element to render said device operative and inoperative.

45. In an elevator system, a weight responsive element associated with a car, arranged to have a tell-tale movement, said car having a gate, a car gate switch controlled by said gate, an electro-responsive actuator for said switch, and means controlled by the tell-tale movement of said element for rendering said actuator effective and ineffective.

46. In an elevator system, a weight responsive element associated with a car, arranged to have a tell-tale movement, said car having a gate, a car gate switch controlled thereby, and an electro-magnetic actuator for said switch, said actuator being controlled in accordance with the tell-tale position of said element to be effective to close the switch with the car unoccupied, and ineffective to close the switch with the car occupied.

47. In an elevator system, a weight responsive element associated with a car, arranged to have a tell-tale movement, said car

- having a gate, a car gate switch controlled thereby, a push-button system of circuits conditioned by operation of either a hall or car button regardless of whether the car gate is open or closed to establish direction for car dispatch and predetermine its stop, car dispatch being effected by closing said gate switch, and an actuator for said gate switch movable to different positions by the tell-tale movement of said element to be effective and ineffective. 5
48. In an elevator system, a weight responsive element associated with a car, arranged to have a tell-tale movement, said car having a gate, manually controlled means to establish direction for car dispatch and predetermine its stop regardless of whether the car gate is open or closed, without effecting car movement, a switch operable by closing to effect car movement, and means operable in accordance with the tell-tale position of said element to control said switch to close and open independently of movement of said element. 10
49. In an elevator system, a weight responsive element associated with a car, arranged to have a tell-tale movement, a car gate, manually controlled means to establish direction for car dispatch and to predetermine a stop without effecting car dispatch, a car gate switch arranged to be actuated by the car gate, and an electro-magnetic actuator for said switch, a part of said actuator being movable by the tell-tale movement of said element to render it effective to close the switch with the car unoccupied to effect car dispatch, and to render it ineffective to close the switch with the car occupied. 15
50. In an elevator system, a weight responsive element associated with a car, arranged to have a tell-tale movement, said car having a gate, a switch, selectively operable push-button controlled circuits exclusive of said switch, reversing switches having operative windings and having a circuit controlled by said switch, and an electro-responsive device to actuate said switch movable by the tell-tale movement of said element to operative and inoperative positions. 20
51. In an elevator system, a weight responsive element associated with a car, arranged to have a tell-tale movement, a car gate, a car gate switch arranged to be actuated by the car gate, selectively operable push-button controlled circuits exclusive of said switch, reversing switches having operative windings and having a circuit controlled by said switch, and an electro-magnet in said push-button controlled circuits arranged to actuate said car gate switch, said magnet being movable to different positions by the tell-tale movement of said element, to be effective to close said gate switch with the car unoccupied and the car gate open, and to be ineffective to influence said gate switch with the car unoccupied. 25
52. In an elevator system, a weight responsive element associated with a car, arranged to have a tell-tale movement, a movable circuit controller on the car, and means connected to and movable with said element to and from a position to effectively actuate said circuit controller. 30
53. A system of control for elevators comprising in combination, a car gate switch, and manually controlled electro-responsive means to close the car gate switch independently of the car gate. 35
- In witness whereof, I have hereunto set my hand this 24th day of March, 1927. 40
